NIGHT LIGHT

Ernest W. Dietz, Torrance, and Herbert L. Kornfeld, Hollywood, Calif., assignors to Pacific Electriccord Company, Gardena, Calif.

Filed June 4, 1973, Ser. No. 365,991

Term of patent 14 years

Int. Cl. D26—05

U.S. Cl. D48—20 E

FIG. 1

FIG. 2

FIG. 3

FIG. 4

FIG. 5

FIG. 6

FIG. 7

FIG. 1 is a perspective view of night light showing our new design;

FIG. 2 is a side elevational view of said night light; FIG. 3 is an elevational view of the side of said night light opposite that shown in FIG. 2;

FIG. 4 is a front elevational view of said night light;

FIG. 5 is a rear elevational view of said night light;

FIG. 6 is a top plan view of said night light; and

FIG. 7 is a bottom view of said night light.

We claim:

The ornamental design for a night light, substantially as shown and described.
